CLAIM

The ornamental design for a dispenser for toy beads, as shown and described.

DESCRIPTION

FIG. 1 is a perspective view seen from the front, top, and right sides of a dispenser for toy beads showing my new design;

FIG. 2 is a perspective view seen from the back, bottom, and left sides thereof;

FIG. 3 is a front view thereof;

FIG. 4 is a back view thereof;

FIG. 5 is a top plan view thereof;

FIG. 6 is a bottom view thereof;

FIG. 7 is a right side view thereof;

FIG. 8 is a left side view thereof;

FIG. 9 is an enlarged perspective view of the portion of FIG. 1 indicated by brackets 9; and,

FIG. 10 is a view similar to FIG. 9 but showing the elements housed within the right end in an extended position.

The dash-dot broken line defines the bounds of the claimed design and forms no part thereof. The dotted lines adjacent to the dash-dot boundary and visible in FIGS. 1-6 and 8 depict the features of the toy bead dispenser that form no part of the claimed design.
